UNITED STATES PATENT OFFICE.

DANIEL V. RAMAZZOTTI, OF SUTTER CREEK, CALIFORNIA, ASSIGNOR TO THE KNIGHT COMPANY, OF SUTTER CREEK, CALIFORNIA, A CORPORATION.

ROAD SCARIFIER.

Application filed September 21, 1926. Serial No. 136,779.

This invention relates to improvements in scarifiers, my principal objects being to provide an implement of this character so constructed that the pull on the drawbar will exert a constant downward pressure on the frame of the implement and consequently on the scarifier teeth, and all pulling strains will be imparted directly to the tooth block; to arrange for raising and lowering the teeth so that they may be accurately regulated and without any lost motion being had; and to mount the teeth in their supporting block so that while rigidly held in place they may be easily removed or adjusted longitudinally at any time.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved scarifier.

Fig. 2 is a top plan view of the same.

Fig. 3 is a transverse section on the line 3-3 of Fig. 1.

Fig. 4 is an enlarged longitudinal section of the forward end of the implement taken on the line 4-4 of Fig. 2.

Fig. 5 is an enlarged fragmentary transverse section showing the mounting of the tooth block adjusting means on the frame and block.

Fig. 6 is an enlarged sectional elevation of the tooth block showing the manner of mounting the teeth therein.

Referring now more particularly to the characters of reference on the drawings, the frame of the machine comprises longitudinal side beams 1 suitably spaced apart. These beams are connected at their rear ends by a cross member 2 and at their front ends by a bolster 3 of heavy rigid construction. The frame is supported adjacent its rear end by wheels 4 suitably mounted relative to the frame.

Turnably mounted in connection with and under the bolster 3 is a turntable 5 having

transversely spaced saddles 6 to which are clamped the axle 7 of the front wheels 8. Ear straps 9 are attached to the turntable just above the saddles, to the forward ends of which straps are pivotally connected the rear ends of forwardly extending bars 10, which converge toward their forward ends and are connected together at such ends. The bolster 3 has forwardly extending and centrally located ears 11 which form the support for a transverse pin 12 on which is mounted a clevis 13. A drawbar 14 projects forwardly from the clevis but is turnably mounted on a substantially vertical pin 15 passed through the drawbar and clevis at the forward end of the latter. The drawbar, which is adapted at its forward end, for connection to a suitable draft means, is longer than the bars 10 and projects through a yoke 16 secured to and projecting upwardly from said bars adjacent their forward ends.

It will therefore be seen that by means of this arrangement the pull on the drawbar is transmitted directly to the rigid bolster. At the same time when the drawbar turns with the turning of the draft means, the bars 10 and hence the wheels 8 will be turned also, so that the implement will be properly steered. Since the drawbar has a downward slant the pull thereon always exerts a downward pull on the bolster and frame.

Extending transversely of the implement under the frame and intermediate the front and rear wheels is a block 17 for supporting a number of scarifier teeth 18 which project through the block at a suitable forward angle to the ground. The teeth fit in slots 19 in the block, taper drifts 20 being driven in the slots ahead of the teeth, there holding said teeth immovable. Besides the drifts however, the teeth are positively held against longitudinal movement, while enabling them to be longitudinally adjusted relative to the block by a transverse rod or bolt 21 removably mounted in said block and engaging any one at a time of a number of vertically spaced and semi-circular notches 22 cut transversely in the back faces of the teeth.

Ears 23 project forwardly from the block 17, bars 24 being secured at their rear ends to said ears and extending in converging

relation thence to a pivotal connection with ears 25 which project rearwardly from the bolster 3. In this manner the dragging strain on the block is taken directly by the 5 bolster and thence by the drawbar, as will be evident.

To raise and lower the block 17, I provide transversely opposed hand wheels 26. Depending from these wheels are screw 10 shafts 27 which are threaded through spherical blocks 28. These blocks have radial trunnions 29 extending transversely of the implement, said trunnions being turnably mounted in vertical slots 29^a formed in supporting members 30 rigidly secured to the frames 1 on the outside thereof. The blocks however are snugly fitted in the supports. The shafts 27 project below these supports, their lower ends carrying spherical heads 20 31 which are universally and snugly turntable in suitable sockets 32 provided in the block 17. It will therefore be seen that upon turning the hand wheels one way or the other the block 17 will be raised or lowered, said block turning upon its pivotal connection of the arms 24 with the ears 25 as an axis. The block therefore moves through an arc, such movement being taken care of by reason of the swivel heads 31 and the 25 turnable blocks 28.

To brace the blocks 17 transversely, ears 33 project upwardly from one end of the block to form a pivotal support for a transverse brace bar 34 which extends thence 30 under and across the frames 1 to a pivotal connection with the opposite end of a transverse beam 35 secured to said frames. As the block 17 is raised or lowered, it moves laterally somewhat, but this movement as far as the screw shafts 27 are concerned is taken care of by the turning of the blocks 28 on a longitudinal axis, enabled to be had

by reason of the vertical movement of the trunnions 29 in the slots 29^a.

From the foregoing description it will be 45 readily seen that I have produced such a device as substantially fulfills the objects of the invention as set forth herein.

While this specification sets forth in detail the present and preferred construction 50 of the device, still in practice such deviations from such detail may be resorted to as do not form a departure from the spirit of the invention, as defined by the appended 55 claims.

Having thus described my invention what I claim as new and useful and desire to secure by Letters Patent is:

1. A scarifier including a frame, wheels supporting the frame, a bolster mounted at the front end of the frame, a tooth-supporting block extending transversely of and under the frame rearwardly of the bolster, arms projecting from the block and pivoted onto the bolster, means for moving the block vertically, a transversely extending brace member pivoted at one end onto the block adjacent one end thereof and extending thence toward the opposite end of the block, and means for pivoting the opposite end of said brace member in connection with the frame. 60

2. A scarifier including a frame, a bolster at the front end of the frame, a transversely extending tooth-block connected to the bolster, a turntable mounted on the bolster, wheels supported from the turntable, bars projecting forwardly from and secured to the turntable, a drawbar pivoted onto and extending forwardly from the bolster, and a yoke attached to the bars through which the drawbar passes. 65

In testimony whereof I affix my signature.

DANIEL V. RAMAZZOTTI.
